Arthur F. Poole.

UNITED STATES PATENT OFFICE.

ARTHUR F. POOLE, OF KENILWORTH, ILLINOIS, ASSIGNOR TO THE WAHL COMPANY, OF WILMINGTON, DELAWARE, A CORPORATION OF DELAWARE.

CALCULATING-MACHINE.

1,318,587.

Specification of Letters Patent.

Patented Oct. 14, 1919.

Application filed January 5, 1918. Serial No. 210,501.

To all whom it may concern:

Be it known that I, ARTHUR F. POOLE, a citizen of the United States, residing at Kenilworth, in the county of Cook and State of Illinois, have invented certain new and useful Improvements in Calculating - Machines, of which the following is a specification.

My invention is an improved calculating machine for the purpose of computing and checking a particular kind of account hereinafter to be more fully described.

The object of my invention is to provide improved means of handling said forms of accounts, to the end that errors may be more readily corrected and the accounts may be computed with less labor than it is possible to compute the same on calculating-machines of the prior art.

20 The particular class of accounts which my machine is adapted to compute are accounts which are written as in the example below:

5.67
7.28
9.35

22.30

It will be noted that this account consists 30 of a series of items written in a vertical column, and that the total of said items is written beneath the column.

One of the objects of my improved machine is to obtain the grand total of a series 35 of accounts written in this manner and also to provide a check in the way of accumulating a duplicate grand total to compare with the grand total obtained by the accumulation of the totals of the primary account.

40 The above and other objects of my invention will be apparent to those skilled in the art from a reading of the accompanying specification.

My invention may be best understood by 45 reference to the accompanying figures, of which—

Figure 1 is a front elevation of a machine equipped with my invention;

Fig. 2 is a perspective view of the arrangement of the vertical and horizontal totalizers, and

Fig. 3 is a development of the numeral wheels of the two cross totalizers employed.

Similar numerals of reference refer to like parts throughout the various figures. 55

In its preferred form my invention is used in connection with the well-known Wahl cross-footing machine which has been extensively placed on the market and the mechanism of which is thoroughly described in 60 the patent of John C. Wahl, Patent No. 1,270,471, filed March 15, 1916, said machine consisting of a jumping or cross totalizer adapted to be brought into co-operation with any one of a series of vertical totalizers, both 65 totalizers being mounted on a typewriter and operated by the typewriter numeral keys. However, the Wahl machine described in 70 said application is modified in several particulars, as will be hereinafter set forth.

Referring particularly to Figs. 1 and 2, 10 represents the typewriter equipped with a Wahl crossfooting attachment 11, said attachment including a vertical actuator 12 and a cross actuator 13. The typewriter is 75 equipped with the usual assemblage of letter and numeral keys. However, I have not shown the letter keys, since these would simply complicate the drawings. The typewriter is also provided with a set of tabulator keys 35. Said keys being the customary tabulator keys present in the Remington machine, it is not necessary to herein describe the structure. 80

The vertical actuator is provided with a 85 vertical master wheel 14, and the cross actuator is provided with the cross master wheel 15. A set of digit keys 16 is provided and each of these keys is connected by a pull rod 17 to the actuator 11 by mechanism thoroughly described in said Wahl application and which it is not necessary to describe in this specification. Vertical depression of any of the digit keys 16 results in a differential rotation of the master wheels 14 and 15 90 a number of spaces determined by the particular digit key 16 which is being operated; for instance, if the 2 digit key is operated, the master wheels 14 and 15 will turn two spaces, etc. The direction of rotation of the 95 vertical master wheel 14 is controlled by a handle 18, this handle being manually settable in any one of three positions determining that the vertical master wheel shall revolve in a direction to add, revolve in a direction 100 to subtract or not revolve at all, this latter

condition corresponding to a disconnect or nonoperating condition of the vertical master wheel 14. Similarly the cross master wheel 15 is controlled by a handle 19, which 5 is also settable to any one of three positions, thus determining additive rotation, subtraction rotation or nonrotation for the cross master wheel 15.

The Wahl machine is also provided with 10 automatic means for determining the direction of rotation of the cross master wheel 15, said means including a roller 20 mounted on the end of a crank arm 21, which is rotatably mounted on a shaft 22 in the vertical actuator. The roller 20 is adapted to be acted on by cams (not shown) attached to the vertical totalizer. Whether or not the roller 20 or the handle 19 is effective in determining the condition of the cross master wheel 15 is 15 determined by the position of an "automatic to manual" shift handle 23. Said handle when in one position determines that the roller 20 shall be effective in controlling the cross master wheel 15, and when in its alternative position determines that the handle 19 shall be effective to a like end.

The Wahl machine is also provided with a universal correcting handle 42, which, when operated, serves to reverse the condition of 20 both the vertical master wheel 14 and the cross master wheel 15. This handle is used for the double purpose of first correcting an error by re-inserting a number in an opposite direction, and second for extracting a 25 total, the handle being thrown to its alternative position, thereby throwing the machine into subtraction and the total exhibited on either the vertical or cross totalizers may be subtracted out.

40 The mechanism by which these handles and the roller 20 control the cross and vertical master wheels has been thoroughly described in the cited application of Wahl and therefore need not be recited here.

45 My improved calculating machine is provided with a vertical totalizer 24 and two cross totalizers 25 and 26. The vertical totalizer is mounted on a truck 27, said truck being attached to the typewriter carriage 28 by suitable connections disclosed in the cited 50 patent to Wahl. The typewriter carriage 28 advances step by step upon the depression of the numeral keys 16 and numbers are inserted into the totalizers *seriatim*, the 55 carriage 28 escaping to the left one step after the operation of each of the digit keys 16.

The cross totalizers 25 and 26 are mounted on a cross truck 29, said truck being slidably mounted in the framework of the machine 60 and having mounted thereon a pickup latch 30, which is adapted to be connected to a heel 31 on the vertical totalizer, thus temporarily advancing the cross truck 29 in synchronism with the main truck 27. The 65 cross truck 29 is drawn to the right by means

of a spring 32, and a cam 33 is provided on the framework of the machine and serves to release the latch 30 when a pin 34 in said latch contacts with the cam 33 during the advance of the truck 27. It is to be noted 70 that in my present invention this release of the cross truck 29 from the vertical truck 27 occurs when the vertical master wheel 14 is two spaces to the right of the lowest decimal place of the vertical totalizer 24.

To illustrate, assume the number 54 is to be entered into the machine. The vertical truck 27 is tabulated by means of the ordinary typewriter keys 35, so that the vertical master wheel 14 is in engagement with the 80 wheel in the tens order of the vertical totalizer 24. The 5-key is then depressed, thus inserting the 5 into the vertical totalizer and also 5 in the tens place of the cross totalizer 26. The 4 digit key 16 is then depressed, 85 thus inserting 4 into the units place of the vertical totalizer 24 and the cross totalizer 26. The carriage then escapes to the sub-units place. However, the cross truck 29 still remains connected to the vertical truck 90 27 for the reason that the pin 34 has not yet been acted on by the cam 33. On the next step of the vertical truck 27 contact is made between the pin 34 and the cam 33. The pickup latch 30 is disengaged from the heel 95 31 and the spring 32 pulls the cross truck 29 to the left until it is stopped by mechanism hereinafter to be described.

The pickup and release mechanism just described is similar to that shown in the cited 100 patent of Wahl, to which the reader is referred for further information, the difference being that in said Wahl case the cross truck is released when the vertical truck has reached the sub-units decimal place. In my 105 present invention this release, for reasons hereinafter to be described, does not occur until the vertical truck has progressed one step farther.

The vertical totalizer 24 has mounted on 110 it a series of tie rods 36, 37, 38 and 39, which serve to support a plate 40 at a distance from the vertical totalizer 24 equal to the distance between the cross totalizers 25 and 26. The plate 40 is provided with a heel 41, which 115 has a function similar to the heel 31 on the vertical totalizer 24, and when the pickup latch 30 is disconnected from the heel 31, the cross truck moves to the right until the latch 30 engages the heel 41. When the 120 latch 30 is in engagement with the heel 41, bringing of the vertical totalizer 24 into cooperation with the vertical master wheel 14 will bring the cross totalizer 25 into coöperation with the cross master wheel 15. Consequently, when the latch 30 is in engagement with the heel 31, any number entered into the vertical totalizer 24 will be entered into the cross totalizer 25, instead of the cross totalizer 26. The cross totalizer 25 is 125 130

provided with its numeral wheels running in the reverse direction, as shown in Fig. 3. The purpose of said reverse numeral wheels will be hereinafter fully described.

5 Having now described the mechanism employed in carrying out my invention, I shall describe its operation.

Assume that a series of bills, like the one given in the beginning of this specification, 10 are to be computed. The first bill to be written is as follows:

5.67	
7.28	
9.35	
15	_____
22.30	

The three items 5.67, 7.28 and 9.35 are first written into the machine, these items being 20 entered into the vertical totalizer and into the cross totalizer 26. It is to be noted that because the cross truck 29 is not disconnected from the vertical truck 27 until said vertical truck has reached the space to the 25 right of the sub-units space, that there will be no disconnection of the vertical and cross trucks during the writing of the three numbers above mentioned. After having written the last number 9.35, the vertical totalizer 24 will exhibit the total 22.30, as will also the cross totalizer 26. After having written the last digit of the number 9.35, the space bar (not shown) of the typewriter is operated, thereby permitting the 30 vertical truck 27 to escape one step to the left of the sub-units place. This step will disconnect the cross truck 29 from the vertical truck 27, and said cross truck will move to the right until stopped by the engagement of the pickup latch 30 with the heel 41. The vertical truck is now returned to the right and it is to be noted that the cross master wheel 15 will now be in coöperation with the cross totalizer 25, when the vertical 35 master wheel 14 coöperates with the vertical totalizer 24. The universal correcting lever 42 is then placed in its alternative position, thereby causing both the cross master wheel 15 and the vertical master wheel 14 to operate in subtraction. The total 22.30 appearing in the vertical totalizer 24 is now 40 printed out, and since the number wheels of the cross totalizer 25 have their numbers arranged in a reverse direction, the printing 45 out of the total in the vertical totalizer 24 will enter said total into the cross totalizer 25, which will accordingly show 22.30. Said total will agree with the total shown in the cross totalizer 26, thus affording a check on 50 the computation as so far made. And it is to be recollected that after writing the first bill we have the vertical totalizer 24 clear, ready to compute the second bill, and the 55 grand total of the bills computed exhibited 60 in both the cross totalizers 25 and 26, the

correspondence of said exhibited totals affording a check upon the work thus far performed.

Now, assume that a second bill, as below, has to be written. 70

7.65
8.72
5.39
_____
21.76
75

The operation is as before, except that the vertical totalizer 24 will exhibit the total 21.76, and the cross totalizer 26 will exhibit the total 44.06, this being the sum of the 80 total of the first bill, 22.30, and the total of the second bill, 21.76. The total, 21.76, appearing in the vertical totalizer 24 is then subtracted out and this act, as hereinbefore described, will add said total to the total 85 already appearing in the cross totalizer 25, which will then exhibit the total 44.06, corresponding to the same total in the cross totalizer 26. Other bills may be written in a similar manner and at the end of a day's 90 run, either the cross totalizer 25 or the cross totalizer 26 will give a grand total of the bills written during the day and the correspondence of the totals exhibited by the cross totalizers 25 and 26 will be a check 95 upon the accuracy of the work performed.

While I have described my invention in its preferred form and also have shown it as operated in connection with the Wahl crossfooting machine, I do not desire that 100 the use of my invention be so limited. It will be found useful in other forms of accounts than the examples herein given and it will also be found useful when used in connection with machines other than the 105 precise structure herein disclosed.

Many variations may be made from the precise structure herein disclosed without departing from the spirit of my invention, 110 since I claim:

1. In a calculating machine, the combination of a totalizer to accumulate sub-totals, a second totalizer to accumulate grand totals, said second totalizer being adapted to be brought into coöperation with said 115 first totalizer during the accumulation of said sub-totals, and means for clearing said sub-totals from said first totalizer and simultaneously entering them into a third totalizer, said third totalizer being provided 120 with wheels numbered in the reverse direction from the arrangement of the numbers on said second totalizer.

2. In a calculating machine, the combination of a jumping decimal carriage, two 125 totalizers within the zone of action of said jumping decimal carriage, means to bring said jumping decimal carriage into coöperation with either of said totalizers at will, a second decimal carriage controlling the op- 130

- eration of said first decimal carriage, said second decimal carriage having connecting stops placed thereon a distance apart equal to the distance between said two totalizers, 5 a third totalizer, and means to enter a number simultaneously into said first and third totalizers or into said second and third totalizers at will.
3. In a calculating machine, the combination of a jumping decimal carriage, two totalizers within the zone of action of said jumping decimal carriage, said totalizers having their parts arranged to progress in reverse directions, means to bring said 10 jumping decimal carriage into coöperation with either of said totalizers at will, a second decimal carriage controlling the operation of said first decimal carriage, said second decimal carriage having connecting 15 stops placed thereon a distance apart equal to the distance between said two totalizers, a third totalizer, and means to enter a number simultaneously into said first and third 20 totalizers or into said second and third totalizers at will.

totalizers or into said second and third 25 totalizers at will.

4. The method of calculating a series of bills whose items and totals are written in vertical alinement, which method consists in providing a single totalizer for the computation of the various bills, a second totalizer for the computation of the grand totals of said items, and a third totalizer with its number wheels arranged in a reverse direction for accumulating the grand totals of 30 the totals of said bills and writing said bills in the following manner: first accumulating the items of said bills in the first and second totalizers and then subtracting the total of said bills from the first totalizer 35 and simultaneously accumulating said totals in the third totalizer without extracting said total from said second totalizer.

In witness whereof I have hereunto subscribed my name.

45

ARTHUR F. POOLE.
